US00D738356S

(12) **United States Design Patent**
Yamada

(10) **Patent No.:** **US D738,356 S**
(45) **Date of Patent:** **** Sep. 8, 2015**

(54) **SPEAKER**

(71) Applicant: **ZORZO CO., LTD.**, Tokyo (JP)

(72) Inventor: **Teppei Yamada**, Tokyo (JP)

(73) Assignee: **ZORZO CO., LTD.**, Tokyo (JP)

(**) Term: **14 Years**

(21) Appl. No.: **29/500,073**

(22) Filed: **Aug. 21, 2014**

(30) **Foreign Application Priority Data**

Jul. 1, 2014 (JP) 2014-014475
